UNITED STATES PATENT OFFICE

146,524

DESIGN FOR A FINGER RING OR SIMILAR ARTICLE

Celia Robbins, New York, N. Y.

Application May 21, 1946, Serial No. 129,953

Term of patent 7 years

(Cl. D45—10)

To all whom it may concern:

Be it known that I, Celia Robbins, a citizen of the United States of America and a resident of the city, county, and State of New York, have invented a new, original, and ornamental Design for Finger Ring or Similar Article, of which the following is a specification, reference being had to the accompanying drawing, forming a part thereof in which

Fig. 2 is a top plan view of the ring in open position;

Fig. 3 is a side elevational view of the ring as shown in Fig. 2; and

Fig. 4 is an edge elevational view of the ring in closed position.

I claim:

The ornamental design for a finger ring or similar article, as shown.

CELIA ROBBINS.
